UNITED STATES PATENT OFFICE.

ERICH H. LICHTENBERG, OF MILWAUKEE, WISCONSIN, ASSIGNOR, BY MESNE ASSIGNMENTS, TO KOEHRING COMPANY, OF MILWAUKEE, WISCONSIN, A CORPORATION OF WISCONSIN.

LIFTING CRANE FOR CONCRETE MIXERS.

1,402,168.

Specification of Letters Patent.

Patented Jan. 3, 1922.

Application filed August 26, 1918. Serial No. 251,413.

To all whom it may concern:

Be it known that I, ERICH H. LICHTENBERG, a citizen of the United States, residing at Milwaukee, in the county of Milwaukee and State of Wisconsin, have invented certain new and useful Improvements in Lifting Cranes for Concrete Mixers, of which the following is a specification.

This invention has to do with machines for building roads, especially concrete roads, and involves primarily the provision of a crane attachment applicable to road or street paving machines of the type commonly in use today and disclosed by United States Letters Patent Reissue No. 13,617 granted September 16th, 1913 and No. 1,141,470 granted June 1st, 1915.

Paving machines of the type above referred to are adapted to be used in connection with narrow gage railways on which travel hopper cars adapted to convey the aggregate materials such as sand and gravel to the paver. The crane attachment proposed by this invention is mounted upon the paving machine which virtually comprises a portable concrete mixing and distributing plant, said crane being designed to facilitate the lifting of the loaded hoppers of the cars running along the temporary railway paralleling the road paving operation. After the loaded hoppers are lifted by the crane the latter is adapted to be moved to carry each hopper over the loading skip or bucket of the paver, whereupon its contents are dumped into the loading skip, the crane swung to carry the hopper back to its truck, and the skip operated to receive the materials and feed the same into the drum of the mixer forming a part of the paver.

The improvements of this invention comprise primarily certain details of construction and operative features of the crane attachment whereby it is most conveniently adapted to be operated in conjunction with the paver and by the motor with which the latter is equipped.

The construction employed to the above end is clearly set forth in the following detailed description and illustrated in the accompanying drawings, in which—

Figure 1 is a side elevation of an end portion of a paving machine embodying my crane attachment, the truck framework and

drum of the table being only partially illustrated; 55

Figure 2 is an end view of the paver, the loading skip not shown, and illustrating more clearly the driving connections between the hoisting drum and the hopper elevating cable;

Figure 3 is a plan view somewhat diagrammatically illustrating the essential parts of the attachment forming the invention, dotted lines illustrating the boom of the crane swung as when carrying the hopper to and from the truck of the car of which the hopper forms a part;

Figure 4 is a sectional view through the boom, showing more clearly the mode of support of the adjustable carrier on the boom.

The general features of the paving machine to which my invention is preferably attached being illustrated in the patents above enumerated will not be additionally described herein, though it may be noted that the paver may be of the type known as the distributing chute machine instead of the boom and bucket type, as these terms are known in the art.

The drawings illustrate a portion of the truck of the machine at A, the same being mounted upon the usual ground wheels B and having the framework C carrying the general operating mechanisms of the machine, also the motor not shown. The mixing drum is denoted D and is adapted to be supplied with the aggregates to be mixed therein by means of a loading skip E. The operating mechanism for said skip may be of the class described in my Letters Patent No. 1,103,788 issued July 14, 1914, or any other suitable construction. Said mechanism preferably includes a hoisting drum 1 suitably supported on a shaft 2 mounted in the bearings in the framework C, said drum having a cable 3 wound thereabout and leading off to suitable driving or pulling mechanism operable from the motor of the machine. The skip E is connected by the cables 4 leading over pulleys 5 at the top of the frame C, with the shaft 2 between said cables 4 winding about small drums 6 adapted to turn with said shaft. The skip 100

E is ordinarily raised by turning of the hoisting drum 1, winding the cables 4 about the drums 6, lowering of the skip being 105

accomplished by relieving the pull on the cable 3 permitting unwinding of the cables 4 from said drums 6.

Mounted on an end of the truck, preferably in a detachable manner, as by means of a bracket 7 seen best in Figure 2, is an arm 8 pivotally connected with the bracket 7 by a pin 9. The arm 8 is ordinarily maintained against pivotal movement by connection of a small plate 10 between the same and the frame C of the machine. The arm 8 forms a support for a mast 11 the lower end of which is suitably journaled upon the arm and the upper end of which is journaled in a suitable bearing on a bracket 12 attached to the upper portion of the frame C. The mast 11 has mounted thereon for horizontal swinging movement therewith a boom 13 preferably made from an I-beam. An adjustable guy wire 14 connects the outer end portion of the boom 13 with the upper end portion of the mast 11 and acts as a customary brace in conjunction with a reinforcing guy wire 15 attached at its lower end to the bottom portion of the mast and at its upper end to the top of said mast and engaging intermediate its ends with an arm 16 projecting from the inner end of the boom 13 in substantial alinement with the latter.

There is mounted for adjustment lengthwise of the boom 13 a carrier 17 equipped with a pair of pulleys 18. This carrier seen best in Figure 4 comprises spaced sides 35 formed with hooks 17^a at their upper portions, said hooks engaging over the lower flanges of the I-beam boom 13. There is attached to the outer end of the boom 13 a cable 19 which passes over the outermost pulley 18 down around a movable suspension pulley 20 up and over the inner pulley 18. From there the cable 19 passes over a pulley 21 on the inner end of the boom, downwards around a pulley 22 adjustably supported by a clutch bracket 23 shiftable longitudinally of the mast 11. From the pulley 22 the cable 19 passes upwardly over a vertical pulley 24, into engagement with a horizontal pulley 25, both of these pulleys being supported at the upper end portion of the mast 11; from thence the cable passes over another pulley 26 and leads from there to the shaft 2 carrying the drums 1 and 6 previously described. The cable 19 is adapted to wind about the shaft 2, the winding in such manner being incident to unwinding of the cables 3 from the drum 6. In this manner I am enabled to utilize the weight of the skip E in descending, as a means for winding the cable 19 about the shaft 2 and it will be later seen that this expedient is employed to utilize the skip E as a device for elevating the hopper or dumping body of a car from its seat upon the truck of the car.

65 The suspension pulley 20 has a bail 27

connected with its axis, which bail has as supports a chain or equivalent suspension device 28, said chain looping about a pivot pin 29 forming a connection between the side members of a grapple device 30. A hook may be provided for the lower end of the chain 28 to facilitate adjustment of the operative suspension length of said chain, thereby correspondingly raising or lowering slightly the grapple device 30. The grapple device 30 comprises the pivotally connected side members previously referred to, said members being formed at their lower extremities with hooks 31 adapted to engage trunnions 32 on the ends of the hopper or body 33 of the hopper car which is designated F. This hopper car F may be of any conventional type quite commonly used today, comprising a wheel truck having seats 34 at its end portions in which seats the hopper-like body 33 is received and readily supported in a removable manner. One of the side members of the grapple device 30 carries a hook 35 capable of engaging with one edge portion of a side of the hopper 33 to prevent the tilting of said hopper after the hooks 31 have engaged the trunnions 32 and elevation of the hopper from its seats 34 accomplished.

The constructional features of the present invention having been set forth, the operation of the mechanism may be briefly described.

Preparatory to using the crane attachment hereof, and to render the upper framework and supported parts of the machine as stable as practicable, a swinging bolt 36 on the side of the truck A remote from the bracket 7, see Figure 2, is positioned to engage the lower flange of one of the side channels forming a part of the truck. Tilting of the truck body laterally and relatively to the supporting bolsters upon which it is mounted is thus provided against, the connection 36 being pivotally attached to the axle section 37 of the truck and a nut being screwed upon the bolt at the end cooperative with the frame portion of the truck.

Assuming that a train of cars F filled with the aggregates for use in the paving machine is adjacent to the paver, upon a track substantially paralleling the road paving operation, the skip E being elevated itself first, the grapple device 30 is of course in its lowermost operative position. The boom 13 of the crane may then be swung laterally relatively to the machine until the grapple device 30 is above the hopper of the car F. The operator will then engage the hooks 31 of said device 30 with the trunnions 32 of the hopper 33, whereupon the operator of the paving machine may permit lowering of the skip E. The lowering movement of the skip E utilizes the weight of the latter to transmit motion to the shaft 2

through the pulleys 6, and causes a winding up on said shaft of the cable 19 which passes over the various pulleys previously set forth. The skip E and the operating connections are of course so arranged that the resultant foot-pounds of the skip E in its descent are much greater than those necessary to raise the hopper 33 and its contents some six or eight inches. The skip having 5 reached the ground and the hopper 33 raised from its seats upon the car F, the boom will be swung to bring the hopper 33 above the skip E, whereupon the hook 35 will be unlatched and the hopper turned over so 10 as to dump the aggregate material therein into the skip. Thereafter the hopper, by swinging the boom 13 outwards, again is restored to a position above its seats upon the car F. The paving machine operator will 15 now elevate the skip E to charge the mixing drum of the machine and by so doing the cable 19 is permitted to unwind from the shaft 2 and the hopper 33 is thus lowered to engage with the car F, or in other words 20 restored to its position resting upon the truck of the car F.

The now empty car F may be pushed forward out of the way, a loaded car moved beneath the grapple device 30, and an operation 25 previously set forth repeated. It is notable that owing to the mounting of the carrier 17 and the method in which the cable 19 is engaged over the pulleys of said carrier, said carrier may be shifted readily 30 inwardly and outwardly along the boom, its position necessarily being dependent upon the distance between a point above the skip E and the track of the railway along which the hopper cars operate. The adjustment 35 of the carrier 17 is allowed for by mere travel of the cable 19 over the pulleys 18.

For controlling the extent to which the cable 19 is paid out, in order to permit the 40 necessary raising and lowering of the hopper 33, the clutch bracket 23 is employed and operates in the well known manner of such brackets to be positioned at different points lengthwise of the mast 11 incident 45 to clutching engagement with said mast. It will be apparent that I advantageously utilize the different diameters of the shaft 2 and pulleys 6 in obtaining desirable leverage whereby the skip E may act to elevate 50 the hopper at the proper time. The mounting of the arm or support 8 and bracket 7 on the truck of the machine is advantageous in readily effecting proper alinement of the mast 11.

Having thus described my invention, what I claim as new is:

1. In a crane of the class described, in combination, a support, cable operating means thereon, a vertical mast mounted on 65 the support, a boom mounted to swing hori-

zontally and carried by said mast, a pulley supporting clutch bracket adjustable on the mast, a grapple device, and a cable secured to the boom and arranged to support the grapple device, the cable engaging the pulley of the clutch bracket and being connected with said operating means. 70

2. In a crane of the class described, in combination, a support, cable operating means thereon, a vertical mast mounted on 75 the support, a boom mounted to swing horizontally and carried by said mast, a pulley supporting clutch bracket adjustable on the mast, a grapple device, and a cable secured to the boom and arranged to support the 80 grapple device, the cable engaging the pulley of the clutch bracket and being connected with said operating means, the supporting relation between the grapple device and cable being established by a carrier mounted 85 on the boom and movable to shift the point of supporting suspension of the grapple device relatively to the boom.

3. In a crane of the class described, in combination, a support, cable operating 90 means thereon, a vertical mast mounted on the support, a boom mounted to swing horizontally and carried by said mast, a pulley supporting clutch bracket adjustable on the mast, a grapple device, and a cable secured 95 to the boom and arranged to support the grapple device, the cable engaging the pulley of the clutch bracket and being connected with said operating means, the supporting relation between the grapple device and 100 cable being established by a carrier mounted on the boom and movable to shift the point of supporting suspension of the grapple device relatively to the boom, and pulleys on the carrier affording a slippage connection between the cable and the carrier. 105

4. In a crane of the class described, in combination, a support comprising a truck engaging bracket, an adjustable mast carrying arm on the bracket, means for holding 110 the mast carrying arm in an adjusted position and a boom supporting mast mounted on the arm.

5. In a crane of the class described, the combination with a support, of cable operating means thereon, a mast mounted on the support, a boom adapted to swing horizontally and carried by said mast, a carrier adjustable along the boom, and provided with guide means, a cable connected with said operating means and boom and engaging the guide means of the carrier, a suspension device associated with the carrier and engaging said cable, a loading skip, means to raise and permit lowering of the skip, and means 115 to connect the skip and cable operating means whereby the skip may operate the suspension device. 120

6. A crane as set forth in claim 1, and an associated loading mechanism involving a 130

skip, means to raise and permit lowering of the skip, and a connection intermediate the skip and said cable operating means such that the skip is capable of actuating the 5 said operating means.

7. In a crane of the class described, the combination with a truck including a running gear and bed, a bracket engaging the running gear, an adjustable mast carrying 10 arm on the bracket, means for connecting the said arm to the truck bed, and a boom supporting mast mounted on the arm.

8. In a crane of the class described, the combination with a support, cable operating 15 means thereon, a vertical mast mounted on the support, a boom carried by said mast, a grapple device associated with the boom, a cable secured to the boom and arranged to engage the grapple device, said 20 cable being connected with the operating means, a clutch bracket adjustably mounted upon the crane, and a guide member carried by the clutch bracket and engaging the cable, the adjustment of the bracket regulating the operative position of the grapple 25 device.

9. In a machine of the class described, a

supporting frame, a frame comprising a suitable mast, a boom carried thereby and adapted to swing laterally, a grapple device 30 for cooperation with a hopper containing a load of material, said grapple device being associated with the boom, a loading mechanism associated with the crane and comprising a skip, operating means common to the 35 crane and to the skip and including an operating shaft mounted on the supporting frame of the machine, an operating cable, a winding drum on said shaft connected with said cable so that the cable may wind on 40 and unwind therefrom, cables connecting the skip with said shaft so that the operation of the winding drum by the operating cable is adapted to raise and lower said skip, and a cable adapted to wind and unwind relatively 45 to said shaft and connected with said grapple device of the crane to raise and lower said grapple device, the raising of the grapple device being caused by the turning of the shaft aforesaid incident to lowering of the 50 skip and unwinding action of the cables connecting said skip with the shaft.

In testimony whereof I affix my signature.
ERICH H. LICHTENBERG.
